UNITED STATES PATENT OFFICE.

JOHN F. O'CONNOR, OF CHICAGO, ILLINOIS, ASSIGNOR TO W. H. MINER, INC., OF CHICAGO, ILLINOIS, A CORPORATION OF DELAWARE.

FRICTION SHOCK-ABSORBING MECHANISM.

Application filed June 8, 1925, Serial No. 35,700. Renewed April 23, 1927.

This invention relates to improvements in friction shock absorbing mechanisms.

One object of the invention is to provide a friction shock absorbing mechanism especially adapted for railway draft riggings, having graduated action during compression of the mechanism, the graduated action including relatively light initial resistance followed by progressively increased resistance.

Another object of the invention is to provide in a mechanism of the character indicated, a plurality of relatively movable friction plates and a friction wedge system, wherein the friction wedge system is movable initially with reference to the plates to effect relatively light resistance and all of the parts are movable as a unit, together with the friction wedge system during a predetermined subsequent portion of the compression stroke to effect increased resistance, followed by a relative movement of the plates to further augment the resistance during the remainder of the compression stroke.

Other objects and advantages of the invention will more fully and clearly appear from the description and claims hereinafter following.

In the drawings forming a part of this specification, Figure 1 is a longitudinal, sectional view of a portion of a railway draft rigging, showing my improvements in connection therewith, the section through the friction shell and elements therewith being taken on two section planes 120° apart. Figure 2 is a front end, elevational view of the shock absorbing mechanism proper. Figure 3 is a vertical, transverse, sectional view corresponding substantially to the line 3—3 of Figure 1. And Figure 4 is a detailed, perspective view of a curved friction plate used in connection with my improved mechanism.

In said drawings, 10—10 indicate channel-shaped center or draft sills of a railway car underframe, to the inner faces of which are secured front stop lugs 11—11 and rear stop lugs 12—12. The inner end portion of the drawbar is designated by 13, to which is operatively connected a hooded yoke 14 of well-known form. The shock absorbing mechanism proper, as well as front and rear followers 15 and 16 are disposed within the yoke. The yoke and the parts therewithin are supported in operative position by a detachable saddle plate 17 secured to the respective draft sills. The friction shell em-

ployed in connection with my improved mechanism is of the cylindrical type and in order to properly center and guide the same between the draft sills a pair of guide plates 18—18 are disposed on opposite sides of the shell, the plates being suitably secured to the corresponding draft sills.

My improved shock absorbing mechanism proper, comprises broadly, a combined friction shell and spring cage casting A; a main wedge B; three friction wedge-shoes C, D and D; two sets of friction plates E and F; a main spring resistance G; a spring follower sleeve H; and a retainer bolt J.

The combined friction shell and spring cage is in the form of a substantially cylindrical casting having a transverse rear end wall 19 adapted to co-operate with the rear follower 16. The friction shell section 20 is formed at the forward end of the casting A, the spring cage proper being formed rearwardly thereof. The friction shell 20 has three interior inwardly converging true cylindrical friction surfaces 21—21.

The wedge B is in the form of a relatively heavy cored block, having a transverse flat front end face 22 adapted to bear on the inner side of the front follower 15. The inner end of the block B has three rearwardly converging wedge faces 23, 24, and 24, the three faces being symmetrically arranged around the axis of the mechanism. The faces 24 are disposed at relatively blunt angles with reference to the longitudinal axis of the mechanism while the face 23 is disposed at a relatively keen wedge acting angle with reference to said axis. As most clearly shown in Figure 1, the wedge block B has a continuous annular laterally projecting flange 25 at the outer end thereof. The three friction shoes C, D and D are of like design, except as hereinafter pointed out. Each of the shoes C, D and D has a longitudinally disposed outer true cylindrical friction surface 26 adapted to co-operate with one of the friction plates E. On the inner side, at the forward end thereof, the shoe C has a wedge face 123 correspondingly inclined to and adapted to co-operate with the wedge face 23 of the block B. The shoes D are each also provided with an inner wedge face at the forward end thereof, the same being indicated by 124. The wedge faces 124 of the two shoes D co-operate with the faces 24 of the block B, being corre-

100
105
110

spondingly inclined thereto. It will be evident that the shoes D and D have their wedge faces disposed at relatively blunt angles with reference to the longitudinal axis of the mechanism while the shoe C has its wedge face disposed at a relatively keen wedge-acting angle with reference to said axis.

The two sets of friction plates E and F are interposed between the wedge shoes and the friction surfaces 21 of the shell. As most clearly shown in Figures 1, 2 and 3, the friction plates of the two sets are arranged in annular series, each set comprising three plates. The three plates E are all of like design, each plate being curved in cross-section and having outer and inner true cylindrical friction surfaces, the inner friction surfaces thereof co-operating with the friction surfaces 26 of the friction shoes. Each of the plates E has a flange 27 laterally projecting therefrom at the rear end. It will be evident that the flanges 27 of the three shoes E form a substantially complete annulus. The flanges 27 are adapted to work in an annular groove 28 provided on the interior wall of the friction shell, the opposite end walls 29 and 30 of said groove limiting the outward and inward movement, respectively, of the plates E.

The friction plates F which are also three in number, are of like design. The plates F are arranged in annular series similarly to the plates E and are interposed between the latter and the friction surfaces 21 of the shell. As most clearly shown in Figure 4, each friction plate F is curved in transverse section and has inner and outer true cylindrical friction surfaces adapted to co-operate respectively with the outer friction surfaces of one of the plates E and the corresponding friction surface 21 of the shell. Each plate F is also provided with a lateral flange 31 at the forward end thereof, the flanges 31 of the three plates F forming a substantially complete annulus. The flange 31 of each plate F is adapted to bear on the outer end of the corresponding friction shoe. It will be seen that the plates F are thus positively returned to their outermost position by the friction shoes.

The main spring resistance element G comprises an outer relatively heavy coil 32 and a relatively lighter coil 33, the inner coil being of greater length than the outer coil. As most clearly shown in Figure 1, the coil 32 bears at the rear end on the inner side of the end wall 19 of the spring cage. The coil 33 has its front and rear ends bearing respectively on transverse flat abutment faces 34 on the friction shoes and the outer end of a hollow boss 35 projecting inwardly from the wall 19 of the spring cage.

65 The spring follower H is in the form of

a cylindrical sleeve having a heavy annular flange 36 at the inner end thereof on which the outer end of the spring 32 bears. The front face of the flange 36 normally engages the rear faces of the flanges 27 of the plates E. It will be evident that outward movement of the spring follower is thus limited by engagement with the rear ends of the plates E, outward movement of the latter being in turn limited by engagement of the flanges 27 thereof with the abutment face 29 of the friction shell. As most clearly shown in Figure 1, a certain amount of clearance is provided between the inner ends of the friction shoes and the outer end of the spring follower sleeve H, thereby providing for a certain amount of preliminary action of the friction shoes. The opening through the sleeve H is of sufficient size to freely accommodate the coil 33 of the spring resistance.

The mechanism is held of uniform overall length by the retainer bolt J which has its opposite ends anchored respectively to the main wedge B and the hollow boss 35 of the spring cage.

In the normal position of the parts which is that shown in Figure 1, the outer ends of the plates F are spaced from the inner face of the annular flange 25 of the wedge block B, the distance between these parts preferably being greater than the clearance between the inner ends of the friction shoes and the outer end of the spring follower sleeve H. The spring 33 is preferably under initial compression, thereby providing for compensation for wear of the various friction and wedge faces of the mechanism. The spring 32 is also preferably under initial compression.

100 The operation of my improved shock absorbing mechanism during a compression stroke is as follows: The front follower 15 and the casting A are moved relatively toward each other, forcing the wedge B and the friction-shoes D-D inwardly of the shell, compressing the spring 33 and at the same time forcing the shoes apart, thereby placing the friction plates E and F under lateral pressure and forcing the same 110 against the friction surfaces of the shell. During the initial inward movement of the follower 15 and the wedge B, there will be substantially no movement inwardly of the friction plates E and F, the spring 32 being of sufficient capacity to yieldingly maintain the plates in their outermost position. During initial action, the friction shoes C, D and D will be forced to slide on the inwardly converging friction surfaces of the 115 plates E. This action will continue until the inner ends of the shoes engage the spring follower H, thus starting compression of coil 32. A slight additional compression brings the flange 25 of the wedge 120

B into engagement with plates F starting them in motion. The plates F will be carried inwardly of the friction shell in unison with the wedge block B. Due to the friction existing between the plates E and the friction shoes and the plates F, the plates E will be carried inwardly in unison with the shoes and the plates F, friction at this time being created between the outermost plates 10 and the friction shell. Inward movement of the two sets of plates and the friction shoes in unison will continue until the flanges 27 of the plates E engage the abutment faces 30 of the casting A, whereupon movement of the plates E will be positively arrested. During the continued inward movement of the wedge B, the friction plates F will be forced to slide relatively to the plates E and the friction shoes will also slide on the last 20 named plates. This action will continue until the actuating pressure is reduced or the main follower 15 engages the outer end of the casting A, whereupon the actuating force will be transmitted directly through 25 the latter to the follower 16, thereby preventing the springs from being driven solid.

It will be evident that there will be substantially no wedging action between the blunt faces of the wedge and the corresponding shoes, while a true wedging action will be effected between the co-operating keen faces of the wedge and the shoe C. Due to the converging relation of the friction shell surface and the consequent converging 35 relation of the friction surfaces of the plates E, there will be a slight lateral approach of the friction shoes toward each other, during compression of the mechanism, the blunt shoes slipping inwardly on the wedge 40 faces of the main wedge. Due to the differential action thus produced, there will be a slight additional compression of the coils 32 and 33 of the main spring resistance. During the wedging action, there will also 45 be a slight expansion of the shell thereby storing up energy therein whereby the shell will forcibly contract when the actuating pressure is removed, creating lateral inward pressure on the blunt faced shoes and facilitating 50 release of the main wedge due to the releasing angle of the co-operating wedge faces of the main wedge and the shoes D.

In release, the springs 32 and 33 effectually restore all of the parts to normal position, the spring 33 forcing the shoes C and main wedge B outwardly until movement of the latter is limited by the retainer bolt J. The friction plates F will be carried outwardly in unison with the shoes C, D and D, inasmuch as the flanges 31 of the plates engage the outer ends of the shoes. Expansion of the spring 32 will carry the plate E outwardly until movement thereof is limited by the abutment face 29.

65 By the employment of the blunt and keen

sets of wedge faces, I am enabled to obtain a very high wedging action during the compression stroke, since the keen wedge faces may be relatively acute without danger of the parts sticking, the blunt wedge faces 70 acting more or less as "safety valves". In this connection, it will be understood by those skilled in the art that my improvements are capable of use in a mechanism either employing a blunt and keen system of 75 wedge faces or wedge faces which are all of the same angle with respect to the axis of the mechanism.

While I have herein shown and described what I now consider the preferred manner 80 of carrying out my invention, the same is merely illustrative and I contemplate all changes and modifications that come within the scope of the claims appended hereto.

I claim:

1. In a friction shock absorbing mechanism, the combination with a friction shell; of a plurality of curved friction plates co-operating with the shell, certain of said plates having limited movement with reference to the shell; an abutment face on the shell adapted to engage with the inner ends of said last named plates for limiting the movement thereof while permitting further movement of the remaining plates; lateral wedge pressure-creating means co-operating with said plates; and a main spring resistance.

2. In a friction shock absorbing mechanism, the combination with a friction shell having interior curved friction surfaces; of an annular series of curved friction plates within the shell, said plates and shell being adapted for limited relative movement; an abutment shoulder on the shell co-operating with the inner ends of said plates for limiting the movement thereof inwardly of the shell; a second annular series of curved friction plates interposed between the first named series and the friction surfaces of the shell; wedge-friction-shoes co-operating with said plates; a main wedge co-operating with said shoes; and spring resistance means cooperating with said shoes and plates.

3. In a friction shock absorbing mechanism, the combination with a friction shell having interior friction surfaces; of a plurality of curved friction plates within the shell, said plates being held stationary during the initial compression of the mechanism, all of said plates as a unit being adapted for bodily movement relative to said shell for a limited distance during a compression stroke; lateral wedge pressure-creating means frictionally co-operating with said plates and having relative movement to said plates and shell prior to movement of said plates with reference to the shell to provide for preliminary action during initial compression of the mechanism; means fixed with

- reference to the shell for arresting movement of certain of said plates at a predetermined point on the compression stroke of the mechanism and thereafter permitting movement 5 of the remaining plates relative thereto; and spring resistance means co-operating with said pressure-creating means and plates.
4. In a friction shock absorbing mechanism, the combination with a friction shell 10 having interior friction surfaces; of a friction wedge system within said shell; sets of curved friction plates interposed between said wedge system and the friction surfaces of the shell, said sets of plates and wedge 15 system being movable as a unit with reference to the shell during a predetermined portion of the compression stroke; means permitting relative movement between said wedge system and plates during the initial 20 compression of the mechanism; abutment means on the shell for limiting the movement of certain of said plates after said predetermined compression and permitting further movement of the remaining plates relative thereto during the remainder of the 25 compression stroke; and spring resistance means co-operating with said wedge system and friction plates.
5. In a friction shock absorbing mechanism, the combination with a friction shell 30 having interior friction surfaces converging inwardly of the mechanism; of a plurality of curved friction plates within the shell and relatively movable thereto; co-operating 35 means on said shell and certain of said plates for limiting relative movement thereof after a predetermined compression of the mechanism while permitting further movement of the remaining plates; a lateral pressure 40 creating means co-operating with said plates and having frictional engagement therewith, said lateral pressure creating means being movable with reference to said plates during initial compression of the mechanism; and 45 spring resistance means, said means maintaining the friction plates stationary with reference to the shell during said initial compression.
6. In a friction shock absorbing mechanism, the combination with a friction shell 50 having interior friction surfaces; a plurality of curved friction plates within the shell; pressure-transmitting means normally spaced from certain of said plates and adapted to 55 engage the same after a predetermined compression of the mechanism; friction shoes co-operating with said plates; wedge means co-operating with said shoes, said wedge means being movable with said pressure-transmitting 60 means and adapted to effect movement of said shoes with reference to said plates during initial compression of the mechanism until relative movement thereof is limited by engagement of said pressure-transmitting means with the plates adapted 65 to be engaged thereby, all of said plates and shoes being thereafter moved bodily inwardly of the shell as a unit during a further predetermined compression of the mechanism; fixed means on the shell for arresting movement of certain of said plates after said further predetermined compression of the mechanism while permitting movement of the remaining plates and said 70 shoes inwardly of the shell during the further compression of the mechanism; and spring resistance means co-operating with said plates and shoes.
7. In a friction shock absorbing mechanism, the combination with a shell having 75 interior friction surfaces; of a plurality of friction plates within the shell; a friction wedge system co-operating with said plates; spring means co-operating respectively with said entire system and plates; and a pressure transmitting spring follower member interposed between said system and the spring means co-operating with said plates for transmitting the pressure directly from 80 said system to said last named spring means.
8. In a friction shock absorbing mechanism, the combination with a friction shell having interior friction surfaces; of a plurality of co-operating friction plates, said plates being bodily movable as a unit with 85 reference to the shell during a predetermined portion of the compression stroke; means yieldingly opposing movement of said plates inwardly of the shell; a friction wedge-system including a spreading member and friction shoes, said shoes co-operating with said plates; spring means resisting inward movement of said shoes; and pressure transmitting means co-operating with said 90 first named means, said pressure means being normally spaced from said shoes and adapted to be engaged by the latter after a predetermined compression of the mechanism to transmit the actuating force from 95 said first named means.
9. In a friction shock absorbing mechanism, the combination with a friction shell; of a plurality of curved friction plates within the shell, said plates being movable bodily as a unit inwardly of the shell during a predetermined compression of the mechanism; means for positively limiting inward movement with reference to the shell of certain of said plates to compel relative movement 100 of said plates after said predetermined compression; friction-shoes co-operating with said plates; wedge-pressure-transmitting means co-operating with said shoes; spring resistance means co-operating with said plates for yieldingly maintaining the same 105 stationary while the shoes are moved inwardly relatively thereto during initial compression of the mechanism; and means interposed between said spring resistance and 110 shoes for limiting said initial relative move- 115
- 120
- 125
- 130

ment of said shoes and plates; and a spring resistance co-operating with said shoes.

10. In a friction shock absorbing mechanism, the combination with a friction shell; of a plurality of friction plates within the shell, said plates being adapted for relative movement and certain of said plates having limited movement with reference to the shell; pressure-transmitting means normally spaced from the remaining plates and adapted to engage the latter after a predetermined compression of the mechanism and move the same inwardly of the shell; a spring resistance; follower-acting means interposed between said spring resistance and plates; a wedge movable with said pressure-transmitting means; wedge-friction-shoes co-operating with the wedge and plates, said shoes having their inner ends normally spaced from said spring follower and adapted to engage said spring follower during the compression stroke of the mechanism, and a second spring resistance co-operating with said shoes.
25. 11. In a friction shock absorbing mechanism, the combination with a friction shell having inwardly converging friction surfaces, said surfaces being curved transversely; of a circular series of curved plates co-operating with said shell friction surfaces; a second circular series of curved plates frictionally co-operating with said first named plates; means on said shell for limiting the movement of said last named plates with reference thereto; wedge-friction-shoes co-operating with said last named plates; means on said first named plates engaged by said shoes for restoring the plates to normal position during release of the mechanism; and spring resistance means co-operating with said shoes and second named plates.
12. In a friction shock absorbing mechanism, the combination with front and rear stops; of front and rear followers co-operating with said stops; a combined friction shell and spring cage co-operating with one of said followers; a yoke enclosing said followers and friction shell; an annular series of friction plates within said shell, certain of said plates having limited longitudinal movement with reference to the shell; means for arresting movement of said last named plates after a predetermined compression of the mechanism, the remaining plates being thereafter movable with reference to the shell and said arrested plates; wedge pressure-creating means for placing said annular sets of plates under lateral pressure; spring resistance means operatively associated with said wedge-pressure creating means; a second spring resistance means co-operating with said plates; and pressure-transmitting means interposed between said last named spring means and friction shoes.

In witness that I claim the foregoing I have hereunto subscribed my name this 29th day of May 1925.

JOHN F. O'CONNOR.
